UNITED STATES PATENT OFFICE.

HERMAN P. ANDRESEN, OF CHICAGO, ILLINOIS, ASSIGNOR TO DAVID J. EVANS, OF CHICAGO, ILLINOIS.

GRAB-BUCKET.

Specification of Letters Patent.

Patented Apr. 13, 1915.

1,134,987.

Application filed April 12, 1911. Serial No. 620,635.

To all whom it may concern:

Be it known that I, HERMAN P. ANDRESEN, a citizen of the United States, and a resident of Chicago, Cook county, Illinois, have invented certain new and useful Improvements in Grab-Buckets, of which the following is a full, true, and exact description.

My invention relates to grab buckets of the class which are provided with positive opening and closing mechanism.

The object of my invention is to provide a grab bucket of this character which will have scoops for digging and carrying material, and which will have powerful opening and closing mechanism for positively and quickly opening and closing said scoops to discharge or take on a load; which will be properly balanced and which will be comparatively light in weight, but exceedingly strong and durable and capable of withstanding the strains to which a bucket of this character is subjected without being distorted or injured, and which will have a minimum number of moving parts and these so arranged and related that the wear and tear on the bucket will be reduced to a minimum and the life thereof greatly increased.

A further object of my invention is to improve the construction and arrangement of the various parts of buckets of the class which constitute the subject matter of Patents No. 870,812 issued to me the 12th day of November, 1907, and No. 921,056 issued to me the 11th day of May, 1909.

My invention will be more readily understood by reference to the accompanying drawings wherein:

Figure 1 is a view in elevation of a grab bucket embodying my invention, parts of this view being broken away to more clearly show the structure of the bucket; Fig. 2 is a top plan view of the bucket shown in Fig. 1; Fig. 3 is an enlarged view in elevation of the bucket frame; Fig. 4 is a sectional view on line 4-4 of Fig. 3 taken in the direction of the arrow; and Fig. 5 is a sectional view looking downward and taken on the line 5-5 of Fig. 4.

The grab bucket of my invention is of the class generally used in the handling of heavy, bulky materials, such as coal, ore, sand, gravel and the like, and for this work it is obvious that a strong, durable, light

weight bucket, preferably of large dimensions and capable of handling large loads of materials, is essential.

The particular bucket shown in the drawings is designed to carry a load generally of from one-half to fifteen tons of material, but of course it is to be understood that, while the size and capacity of the bucket is not essential to my invention, it is one of my objects to make possible the construction of a comparatively light weight bucket of large dimensions and capable of handling heavy loads without becoming damaged or distorted by the strains incidental to such heavy loads.

Preferably my invention consists in a bucket having a frame and two digging and carrying scoops pivoted to the upper portion of said frame, together with mechanism supported by the frame for positively closing the scoops together for digging and carrying a load, and mechanism for opening the scoops and spreading them widely apart.

The particular bucket shown in the drawings is adapted to the numerous "two-line" equipments or hoisting rigs throughout the country, but it is to be understood that my invention is equally adaptable to other hoisting rigs, such for instance as shown in my Patent No. 870,812 above mentioned.

Referring now to Fig. 1, it will be seen that the two scoops A are of substantially triangular shape and are pivotally mounted by means of shafts A' at opposite corners of the frame B, this arrangement permitting the buckets to be widely opened or spread apart, as shown in dotted lines, for the purpose of discharging the load or when the bucket is dropped upon a pile of material preparatory to taking a load. The lower portions of the scoops are made in such form that when their cutting edges A'' are brought together they form a single receptacle wherein the material is retained.

The bucket is suspended and the operation thereof is controlled by means of cables C and D. The two strands D constitute what I term the closing cables. These two strands act together in the same manner as a single strand so far as the closing of the bucket is concerned, but the two cables possess the advantage over a single cable in that I am enabled to increase the lifting strength and retain the inherent flexibility

- of a small cable. Furthermore the use of two cable strands operating together as one cable, but spaced apart makes it possible to better prevent the bucket from turning 5 while it is suspended. Each of the scoop members A is provided with a laterally projecting arm or extension E near its pivotal point, these being connected by chains or links E' to the end of the opening cable C 10 for the purpose of opening the bucket. Thus it will be seen that when the closing cables D are slackened relatively to the opening cable C the scoops will be swung on their pivots and spread widely apart, as 15 shown in dotted lines.

I prefer to make as much as possible of the entire bucket of sheet steel, angles and channels suitably riveted together for the reason that these parts may be cut and 20 formed from stock material. Furthermore, this class of material is not only exceedingly strong, but it is comparatively light in weight. As previously mentioned, the upper ends of the scoops, which are formed by the meeting upper ends of the end plates A'', and inner angles A''' of respective 25 scoops, are pivoted at the corners of the frame B. This frame is preferably substantially wedge-shaped so that it will take up a minimum amount of room between the two 30 scoops. It carries the scoop closing mechanism hereinafter described.

Referring now more particularly to Figs. 3, 4, and 5, the frame has two outer or end plates 1, which are triangular in shape. These plates are connected at their upper 35 ends by a top plate 2 the ends 2' of which are turned downwardly parallel with and riveted along the upper ends of the outer plates 1. Narrow strips or plates 3 are riveted on the inner faces of these downwardly turned ends for the purpose of additionally strengthening the corners of the frame and the bearings for the pivot shafts A' of the 40 scoops. A shaft 4 extends between the two end plates of the frame and is fastened in the lower ends thereof, cotter pins 4' being provided for retaining the shaft in position. A long cylinder or chain drum 5 revolves 45 on this shaft and midway of the ends of this drum and rigidly-attached thereto is a larger operating or cable drum 6, these drums constituting part of the closing mechanism.

For the purpose of stiffening and strengthening the end plates I rivet angle irons 7 on the inner faces thereof adjacent the edge of the plates, thus providing the plates with instanding flanges or ribs. The angles, as 50 will be seen, start immediately adjacent the plates 3 and follow down along the edges of the end plates to a point somewhat above the chain drum 5 from whence they turn across the plate and up along the opposite side, thus assuming a U-shape. Intermediate 55 ate the end plates, and parallel thereto, I

provide two other but shorter plates 8. These intermediate plates are of substantially the shape of the U-shaped angles 7 just described, as shown in Fig. 4, and they are also provided with similar U-shaped 60 angles 9. The purpose of these intermediate plates is to brace the frame against twisting or distorting forces when the bucket is in operation, and in addition to provide bearings for the journals on the 65 centralizing cable sheaves 10 in the upper portion of the frame. These plates rise to the under face of the top plate 2, and each carries a transverse channel beam 11, the 70 upper flanges of which are riveted to the top plate 2, as clearly shown in Figs. 3 and 4. These beams not only serve as means for connecting the intermediate plates to the top plate and add strength to the frame, but they take the lateral thrust exerted by the 75 closing cables D on account of the bends therein at the sheaves 10, (see Fig. 1).

In order to complete the rigidity of the frame and render it absolutely non-distortable, I place a broad plate 15 on each side of 80 the frame. The length of these plates is substantially equal to that of the width of the frame and they are firmly secured by rivets or otherwise to the instanding flanges of the angles 7 and 9. The strains occasioned by the closing chains 18 in closing the bucket are resisted by these plates acting as beams. The plates also act in conjunction with the top plate 2 to resist torsional strain and in consequence greatly rigidify the 85 structure. I rivet L-shaped pieces or brackets 16 upon the lower inner faces of the end plates 1. The longer arms of these L-shaped pieces extend downwardly to the lower ends of the plates 1 and serve to 90 stiffen the same and to increase the size of the journal bearings for the drum shaft. The short arms 16 of these L-shaped pieces project horizontally inward immediately below the flanges of the angles 7, and provide 95 shelves or supports to which are secured the ends of a bridge beam or bottom member 17. I prefer to secure the ends of this bridge member both to the short arm 16' and the inwardly turned flanges of the angles 7. 100 This bridge member preferably consists of a flat strap of steel, and has a centrally up-standing loop or U-shaped bend disposed 105 between the two intermediate plates 8 for the purpose of clearing the cable drum and allowing it to properly operate. This bridge is also riveted to flanges of the angles 9 which are attached to the intermediate 110 plates 8 and its vertical portions 17' are riveted to the respective plates 8 (Figs. 3, 4, 115 and 5). The function of this bridge member is to form a firm and strong mounting for the dead ends of the chains of the closing mechanism, as hereinafter described.

In order to accommodate the two lifting 120

and closing strands or cables D with the required number of turns, I make the periphery of the operating or cable drum 6 broad enough so that the two strands may be wound around it in parallel, and I provide flanges 6' on this drum to prevent the displacement of the cables. The closing cables, as before mentioned, pass downward through a suitable opening in the top plate and over the grooved centralizing sheaves 10, thence down around the cable drum to which their ends are secured. By this arrangement the pulling of the cable rotates the drum and the smaller chain drums are rotatable therewith. This motion is communicated to the scoops for closing them by means of two sets of co-directionally wound closing chains 18. These chains are substantially of the same length, and two of them are wound upon each end of the chain drum 5. One chain on each side of said cable drum is connected to the same scoop so that each scoop has two closing chains (Figs. 1 and 2). The inner ends of the chains are secured to eye-lugs 5'. The chains extend from the drum over sheaves 19 provided therefor on the inner sides of the scoops. From these sheaves the chains pass back to the frame where they are dead-headed or connected to eye-lugs 20 and 20' which are carried upon and firmly secured to the bridge member 17. This arrangement gives a two to one operating ratio between the drum and the scoops and in consequence a very powerful and positive scoop closing mechanism is provided. The closing chains for each scoop are arranged symmetrically upon the chain drum 5 on opposite sides of the cable drum 6, at substantially equal distances therefrom, thus assuring a balanced non-racking application of closing force. I provide for this balanced arrangement of chains for both scoops by placing the chains for one scoop adjacent to the outer ends of the drum 5 and the chains for the other scoop adjacent to the cable drum. The corresponding chain anchoring lugs on the bridge-beam 17 and on the chain drum 6 for the several chains respectively are arranged to facilitate free helical winding of the chains on the drum. To provide for this the lugs for each chain are staggered somewhat, thus providing a suitable space longitudinally on the drum 6 for the winding of each chain. It will be seen that this construction employs the fewest possible number of moving parts, hence the wear and tear, which is due usually to grit and dirt finding its way into the bearings, is accordingly reduced to a minimum and the life of the bucket considerably increased. The eye-lugs upon which the closing chains are dead-headed preferably comprise small blocks of metal provided with an eye at one end to which the chains may be attached, and with a slot in which the bridge 17 fits. By suitably riveting

these blocks to the bridge member (Figs. 3, 4 and 5) there is no chance of their becoming detached.

It will be noted that the pull of the chains is substantially edgewise of the bridge member 17 hence this bridge will stand enormous strains without bending or becoming distorted. For the purpose of preventing excessive slack of the closing cable, and the displacement thereof from the drum, I provide a guard. This guard consists of two flat straps or bands 21' bent to conform to the periphery of the drum and having their upper ends 21" bolted to the side plates 15, as clearly shown in Figs. 3 and 4. The lower ends of these guard straps are connected together by a loop 23 of strap metal. U-shaped pieces of metal 22 riveted to the guard stem are also provided for preventing lateral movement of the guard.

As previously mentioned, the upper ends of the scoop members are mounted upon the projecting ends of the pivot shafts A', one of these shafts being provided for each scoop and having its journal bearings 25 in the upper corners of the end plates 1. These shafts extend the entire width of the frame. The short axles or shafts 12 and 27 of the sheaves 10 and 26 respectively are journaled in the channel beams 11 and the said sheaves 95 revolve thereon. In order to prevent the cables from becoming displaced from these sheaves I provide an extra pair of small idler sheaves 26 similar to but smaller than the cable sheaves 10 and are mounted on short 100 shafts 27 journaled in the channel beams 11.

As many modifications of my invention will appear to one skilled in the art I do not desire to be limited to the structure shown in the drawings.

I claim:

1. In a grab bucket a frame and scoop members pivoted upon the upper portion of said frame, in combination with scoop operating mechanism comprising a chain 110 drum rotatably mounted in the lower portion of said frame, a bridge member in said frame disposed above said drum, and operating chain loops extending from said scoops, co-directionally wound upon said 115 drum and each having an end anchored to said bridge.

2. In a grab bucket a frame and shafts journaled in the upper portion thereof, in combination with scoops mounted upon said 120 shafts and adapted to be closed together to form a receptacle for carrying material, a rotatable drum mounted in the lower portion of said frame between said scoops, sheaves mounted in said scoops, a bridge 125 member in said frame above and parallel to said drum, closing chains secured to said drum passing from said drum around said sheaves and connected to said bridge, and means for rotating said drum to wind the 130

43
chains co-directionally thereon for closing said scoops.

3. In a grab bucket a frame and scoops pivotally mounted at the upper end thereof on opposite sides and adapted to be brought together for digging and carrying material, a rotatable chain drum positioned in the lower portion of said frame and between said scoops, a bridge member forming a part of said frame and disposed above and adjacent to said drum, operating chains secured to said drum extending therefrom to said scoops and back to said bridge, said chains being connected to said bridge at points substantially corresponding to their position on the drum, and a cable drum for rotating said chain drum.

4. In a grab bucket a pair of scoops adapted to be closed together for carrying material, in combination with a frame positioned between said scoops and upon which said scoops are pivotally mounted, said frame comprising end plates and intermediate plates arranged parallel to one another, a bridge member firmly secured to the lower portion of said plates, a top plate connecting the upper ends of said plates, and broad plates extending along the sides of said frame and firmly secured to said end and intermediate plates for preventing distortion of said frame.

5. In a grab bucket a pair of scoops adapted to be closed together for carrying material, in combination with a frame positioned between said scoops and upon which said scoops are pivotally mounted, said frame comprising two end plates and two intermediate plates arranged parallel, a beam firmly secured to and held by the lower ends of said plates, a top plate connecting the upper ends of said end and intermediate plates, broad strain plates extending along the side of said frame and firmly secured to said end and intermediate plates for preventing distortion of said frame, and parallel strengthening beams fastened to the upper portion of said intermediate plates and to said top plate.

6. In a grab bucket a pair of scoops adapted to be closed together for carrying material, in combination with a frame positioned between said scoops and upon which said scoops are pivotally mounted, said frame comprising two end plates and two intermediate plates arranged in parallel and spaced apart, a beam bar firmly secured to the lower portions of said plates, a broad top plate connecting the upper ends of said end plates and intermediate plates, broad plates extending along the side of said frame and firmly secured to said end and intermediate plates for preventing distortion of said frame, parallel strengthening beams fastened to the upper portion of said intermediate plates and to said top

plate, and scoop closing mechanism supported in said frame below said bar and comprising a rotatable chain drum, and operating chains extending therefrom to said scoops.

7. In a grab bucket a frame comprising two end plates, a top plate, and a bridge plate extending between and bracing the lower portions of said end plates, intermediate plates extending between and connected to said bridge plate and top plate, stiffening angles on opposing faces of said end and intermediate plates, and a brace plate extending along each side of said frame and fastened to said angles for preventing distortion of said frame.

8. In a grab bucket a frame comprising two end plates, a top plate and a bridge plate extending between and bracing the lower portions of said end plates, intermediate plates parallel to said end plates, extending between and connected to said bridge plate and top plate, stiffening angles on said opposing faces of said end and intermediate plates and adjacent the edges thereof, a broad side plate extending along each side of said frame and fastened to said angles for bracing said frame against distortion, scoops pivoted at the upper portion of said frame, cable-operated, scoop-closing mechanism mounted in the lower portion of said frame below said bridge, cable centralizing sheaves in said intermediate plates at the upper portion thereof, and channel beams transverse of said intermediate plates and secured to said top plate, said channel beams being adapted to take the lateral thrust of said sheaves.

9. In a grab bucket, a substantially triangular frame, comprising a top plate, triangular end plates depending from the ends of said top plate, intermediate shorter plates depending from the central portion of said top plate, a bridge member extending between and fastened to said end plates above the lower ends thereof, said bridge member having a central U-shaped portion upstanding between and fastened to the lower portions of said intermediate plates, a long drum journaled in the lower ends of said end plates, and a larger cable drum centrally positioned thereon and entering the U-shaped portion of said bridge.

10. In a grab bucket, a substantially triangular frame, comprising a top plate, triangular end plates depending from the ends of said top plate, shorter triangular plates depending from said top plate intermediate said end plates, a bridge member extending between and secured to said end plates above the lower ends thereof, said bridge member having a central U-shaped portion upstanding between and secured to the lower ends of said intermediate plates, a chain drum journaled in said end plates below said

bridge, a larger cable drum centrally positioned thereon and entering said U-shaped portion of said bridge, oppositely swinging scoop members pivoted at the upper portions of said frame and having scoop portions adapted to be closed together below said frame to form a receptacle for carrying material, a pair of chains extending from said drum to each of said scoops having their ends returned and anchored to said bridge member for closing said scoops upon the rotation of said drum, and means for opening said scoops.

11. In a grab bucket a frame comprising a top plate, end plates and a bottom member all firmly fastened together, in combination with instanding flanges on the inner faces of said end plates adjacent the edges thereof, broad side plates riveted to said flanges for preventing distortion of the frame, cable sheaves in the upper central portion of said frame, frame-strengthening beams wherein said sheaves are journaled and adapted to take lateral thrust exerted by suspending cables on said sheaves, vertical plates connected to said beams and said bottom member, extensions depending from the lower end of said frame, a drum rotatably mounted in and disposed between said extensions, a central drum carried on said drum and adapted to receive bucket suspending cables and to be rotated thereby, scoops pivoted at the upper portions of said frame, chains extending from said drum to said scoops for closing said scoops together when said drum is rotated, and lateral extensions on said scoops to which a bucket opening cable is connected for opening said scoops.

12. In a grab bucket a frame comprising a top plate, end plates and a bottom bridge member secured together, in combination with instanding angles riveted on the inner faces of said end plates adjacent the edges thereof, and broad side plates riveted to said flanges for preventing distortion of the frame, cable sheaves in the upper central portion of said frame, frame stiffening beams wherein said sheaves are journaled, and adapted to take lateral thrust exerted by suspending cables on said sheaves, vertical plates riveted to said beams and said bottom member, extensions depending from the lower ends of said end plates, a drum rotatably mounted in and disposed between

said extensions, a central cable drum carried on said drum and adapted to receive bucket suspending cables and to be rotated thereby, scoops pivoted at the upper portions of said frame, chain loops extending from said drum to said scoops for closing said scoops together when said drum is rotated, lugs on said bottom member of said frame to which the ends of said chains are connected, and lateral extensions on said scoops to which a bucket-opening cable is connected for opening said scoops.

13. In a grab bucket the combination of a frame member comprising end plates stiffened with angles and connected by side plates and a top plate, a drum rotatably mounted in the frame, a strap extending from end plate to end plate over the drum and scoops swingably mounted on the frame in combination with operating chains connected to said drum extending to respective scoops and back to dead-end connections on said cross member over the drum.

14. In a grab bucket the combination of a frame comprising end plates held in spaced relation by side and top plates, an operating drum rotatably mounted in the frame, a strap member extending between the end plates and arranged adjacent said drum, scoops swingably mounted on the frame and chains for closing the scoops connected to the drum extending around sheaves on respective scoops and back to spaced dead-end connections upon said strap.

15. In a grab bucket the combination of a rigid frame member, scoops swingably mounted on said frame, said frame comprising end plates connected by side and top plates, an operating drum rotatably mounted in the lower part of the frame, a strap member extending from end to end of the frame over said drum, braces extending between the strap member, and the said upper plate connecting the end members, and closing chains connected to said drum extending around sheaves on respective scoops and back to dead-end connections upon said cross strap.

In testimony whereof, I have set my hand, this 23d day of February, 1911, in the presence of two subscribing witnesses.

HERMAN P. ANDRESEN.
